Patented Oct. 27, 1914.

UNITED STATES PATENT OFFICE.

SALAMON UNGER, OF NEW YORK, N. Y.

PARQUET FLOORING.

1,115,039.

Specification of Letters Patent.

Patented Oct. 27, 1914.

Application filed January 21, 1914. Serial No. 813,469.

To all whom it may concern:

Be it known that I, SALAMON UNGER, a citizen of the United States, and resident of the city of New York, in the county of New York and State of New York, have invented certain new and useful Improvements in Parquet Floorings, of which the following is a specification.

The present invention relates to improvements in wooden floorings, and more particularly to that type which is termed "parquet flooring."

If a parquet flooring is to be laid upon a cement, stone, or similar substratum, first a foundation floor, that is to say an ordinary wooden floor, must be laid on top of such substratum, and upon this ordinary floor are then laid the wooden tesserae or blocks, the parquet flooring so formed being attached to the foundation floor in the well known manner. Such work comprises two distinct and separate operations, that is to say the construction of the foundation floor and the laying of the parquet flooring. In laying the parquet flooring, each wooden tessera must be separately attached to the foundation floor and interlocked with those adjoining it.

One of the objects of the present invention is to construct a parquet flooring for use upon a cement, stone or similar substratum, which does away entirely with the foundation flooring, or rather combines the foundation flooring and the parquet flooring in one integral structure.

Another object of the invention is to provide a parquet floor construction of the character specified, which is comparatively inexpensive, and the laying of which can be effected in a comparatively short time with little labor, and still is both in appearance and durability equal to those heretofore in use.

With these and other objects in view, which will more fully appear as the nature of the invention is better understood, the same consists in the combination, arrangement and construction of parts hereinafter fully described, pointed out in the appended 50 claims and illustrated in the accompanying drawings, it being understood that many changes may be made in the size and proportion of the several parts and details of construction within the scope of the appended claims without departing from the

spirit or sacrificing any of the advantages of the invention.

One of the many possible embodiments of the invention is illustrated in the accompanying drawings, in which:—

Figure 1 is a plan view of a parquet flooring constructed in accordance with the present invention; Fig. 2 is a section taken on line 2—2 of Fig. 1; Fig. 3 is a section taken on line 3—3 of Fig. 1; Fig. 4 is a plan view 65 of an element of the flooring; and Fig. 5 is a section taken on line 5—5 of Fig. 4.

In the drawings, the numeral 10 indicates the cement or stone substratum, in which are formed, preferably, equidistantly holes 11, 70 11, into which are driven wooden plugs or wedges 12, 12. Upon the cement are placed at proper distances furring strips 13, 13, to provide an air space between the cement and the parquet flooring. These strips may 75 be held in position upon the cement by any suitable means.

The parquet flooring comprises flooring boards 14, 14, which correspond in length to the width of the room which is to be provided with a parquet flooring. Each of these boards is composed of two longitudinal strips 15, 15, having grooves 16, 16 in their inner faces, said grooves accommodating the tongues 17, 17 of transverse blocks 18, 18. 80 The blocks 18, 18 are interconnected by grooves 19 and tongues 20. The object of making these boards of longitudinal strips and transverse blocks is to provide a structure which is not warped or distorted by 90 heat or moisture. The upper faces of the strips 15 are provided with longitudinal grooves 21, 21, which extend throughout the length of the said strips and accommodate locking strips 22, which are T-shaped 95 in cross section, and adapted to be fastened to the wooden plugs or wedges 12. The upper surfaces of the flooring boards are cov-

ered by a layer of tesserae, that is to say small wooden pieces or blocks 23, 23, said 100 tesserae being cemented to the flooring boards 14 and to each other by a wood cement, or are fastened thereto and to each other by any other suitable means. The wooden blocks or pieces 23 may have any regular 105 geometric form to produce an artistic design.

In laying the flooring, first the desired number of holes 11 is drilled at suitable intervals in the substratum 10. Into these 110

holes are then driven the wooden plugs or wedges 12, after which the furring strips 13 are put upon the substratum. The flooring boards 14 are then cut to the proper lengths, 5 and placed side by side upon the furring strips throughout the width of the room in parallel relation to each other at suitable distances, to provide proper spaces for the locking strips 22. It is to be observed that 10 the wooden pieces or blocks 23 are secured to the flooring boards before the latter are cut to the proper length. The T-shaped strips are then engaged with the longitudinal grooves 21, 21 in the flooring boards and 15 securely fastened to the cement substratum by means of screws 24, or other fastening devices, which are driven through the said strips into the plugs or wedges 12. After 20 this operation wooden pieces or strips 25 are attached by suitable cementing means, or otherwise, to the upper faces of the locking strips 22, thereby concealing the fastening means 24. The outer faces of the pieces or strips 25 are arranged flush with those of 25 the wooden pieces or blocks 23, whereby a parquet floor is obtained which is in appearance identical with those heretofore in use. The design of the wooden pieces or strips 23 and 25 may be varied, and the 30 said pieces or strips may be either of the same color or of different colors to suit the requirements.

From the foregoing it will be observed that, in constructing this parquet flooring, 35 the foundation flooring, which is to be placed upon a cement or stone substratum, is entirely done away with, or rather the foundation flooring and the parquet flooring are combined into one integral structure. It will be observed furthermore that 40 due to this combination, much material is saved, and, inasmuch as the wooden blocks or pieces 23 are previously attached to the flooring boards 14, the flooring can be laid 45 in a comparatively short time with little labor, and involving small expense. Moreover, since the tesserae 23 are not interlocked, the cost of the structure is still further reduced.

50 What I claim is:—

1. The combination with a cement substratum, of furring strips placed thereon, flooring boards provided with longitudinal

grooves in their upper faces placed side by side upon said furring strips in parallel relation and close to each other, the upper faces of said flooring boards being covered by wooden tesserae, locking strips T-shaped in cross section attached to said cement substratum and fitting the grooves in said flooring boards, and wooden strips secured to the upper faces of said locking strips, the outer surfaces of said wooden strips being flush with those of said tesserae. 55

2. The combination with a cement substratum having holes therein, of plugs driven into said holes, furring strips placed upon said substratum, flooring boards provided with longitudinal grooves in their upper faces placed side by side upon said furring strips in parallel relation and close to each other, the upper faces of said flooring boards being covered by wooden tesserae, locking strips T-shaped in cross section fitting the grooves in said flooring boards, fastening devices driven through said locking strips into said plugs, and wooden strips secured to the upper faces of said locking strips covering said fastening devices, the outer surfaces of said wooden strips being flush with those of said tesserae. 70 75

3. The combination with a cement substratum, of furring strips placed thereon, flooring boards provided with longitudinal grooves in their upper faces placed side by side upon said furring strips in parallel relation and close to each other, each flooring board being composed of two longitudinally rabbeted strips and of a plurality of transverse blocks having tongues in engagement with said rabbets, the upper faces of said flooring boards being covered by wooden tesserae, locking strips T-shaped in cross section attached to said cement substratum and fitting the grooves in said flooring boards, and wooden strips secured to the upper faces of said locking strips, the outer surfaces of said wooden strips being flush with those of said tesserae. 80 85 90 95

Signed at New York, in the county of New York and State of New York, this 7th day of February, A. D. 1913.

SALAMON UNGER.
